UNITED STATES PATENT OFFICE.

GLENN S. WILLIAMSON, OF CEDAR GROVE, NEW JERSEY. ASSIGNOR TO SHUR LOC ELEVATOR SAFETY CO., INC., OF NEW YORK, N. Y., A CORPORATION OF NEW YORK.

ELEVATOR.

Application filed June 15, 1922. Serial No. 568,896.

To all whom it may concern:

Be it known that I, GLENN S. WILLIAMSON, a citizen of the United States, and a resident of Cedar Grove, Essex County, New Jersey, have invented certain new and useful Improvements in Elevators, of which the following is a specification, reference being had to the accompanying drawings, forming a part hereof.

This invention relates particularly to the operation of the car doors and of the shaft doors of elevators and has for its general object the provision of improved power actuated means for the operation of such doors under the control of the operator, whereby the doors shall be opened and closed quickly, suitable provisions being made for the interlocking of the door controlling and operating devices with the car controlling mechanism so as to guard against accidents. In accordance with the invention there is provided an air compressor which is in operative relation with some moving part of the elevator mechanism so that it shall be driven when and only when the elevator car is moved and by the same power which moves the elevator car, regardless of the direction of movement of the car. Through suitable transmitting devices the power thus developed is made to move the car door and the shaft door, or either of them, in either direction at the will of the operator. The invention will be explained more fully hereinafter with reference to the accompanying drawings in which it is illustrated, and in which—

Figure 1 is a view in elevation of an elevator car equipped with devices adapted for the practice of the invention, the car being shown as if with the side nearest the observer removed, a relatively fixed cable being also shown.

Figure 2 is a view from the right hand of the compressor shown in Figure 1.

Figure 3 is a somewhat diagrammatic view of devices for controlling the movement of the traveller by which the elevator and shaft doors are operated, a portion of the car controlling devices being also shown in relation therewith.

Figure 4 is a detail view of a portion of the devices shown in Figure 3.

Figure 5 is a view in side elevation of the power cylinder for operating the doors

with some of its connections and controlling devices.

Figure 6 is a top view of the same with the controlling valve in horizontal section.

Figure 7 is a detail view of a portion of the controlling valve.

Figures 8, 9 and 10 are detail views illustrating particularly the devices for effecting operative engagement between the shaft door and the door operating device, Figure 9 being a view in vertical section on the plane indicated by the broken line 9—9 of Figure 8 and Figure 10 being a view in horizontal section on the plane indicated by the broken line 10—10 of Figure 8.

In Figure 1 of the drawings there is shown at *a* a portion of the frame or body of an elevator car of ordinary construction, the floor being indicated at *a'*. It is assumed that the car is raised and lowered by any usual or suitable means sufficiently indicated at *o*, *o'* in Figure 1, since the present invention is not concerned therewith. The car is shown as having a door *a*² of ordinary construction and a controller box *a*³ with a handle *a*⁴ and an interlocking rod *a*⁵ which operates in the usual manner to prevent the movement of the controller handle to start the car when the car door or the shaft door is not in closed position. At each shaft landing there is a suitable door *b*, indicated in part in Figure 9, which, like the car door *a*², is movable horizontally to open or to close the shaft opening.

In the embodiment of the invention illustrated in the drawing, as a suitable means for the operation of the compressor hereinbefore mentioned, a relatively fixed cable *c*, which may have its lower end connected by a spring *c'* to some relatively fixed point and its upper end connected by a turnbuckle *c*² to another relatively fixed point in the elevator shaft, is passed with several turns, so as to secure the necessary frictional engagement, about a driving drum *c*³ and an idler *c*⁴. The driving drum *c*⁵, by which, in the movement of the elevator car up or down, the hereinbefore mentioned compressor is driven, may have a sprocket wheel *c*⁵¹ for engagement with a chain *c*⁶ which in turn engages a driving pinion *d'* on the shaft of a suitable air compressor *d* which, in the illustrated embodiment of the invention, is carried by the car, preferably supported by a

frame d^2 secured to the under side of the car floor. Also supported by the car and connected with the compressor by a suitable pipe e' , flexible or otherwise, is a storage tank e , in which air compressed by the compressor d may be accumulated for use as required, the tank being provided with a suitable safety valve e^2 and gauge e^3 .

Air under pressure is supplied from the tank e to a power cylinder f which is also mounted on the car and movement is transmitted from the piston f' by suitable means, preferably such as will presently be described. The details of the means for directly controlling the movements of the piston f' under the influence of the compressed air, do not themselves form part of the present invention and are shown in Figures 5, 6 and 7 and described generally herein only for the purpose of enabling the operation to be understood clearly. As shown, the air supply pipe is connected to the chamber of a valve indicated generally at g , by the oscillation of the stem g' of which the air is admitted or exhausted at one end or the other of the cylinder, so as to move the piston in one direction or the other at the will of the operator, by whom the spindle g' is oscillated in one direction or the other. In the arrangement shown the piston rod f^2 is suitably connected to one of the joints of a lazy-tongs h , one end of which is connected, as at h' , to a fixed point on the car, while the other end is connected, as at h^2 , to a traveller k^4 which is mounted in suitable guides k^5 to move horizontally across the car and is connected, as by an arm k^6 , with the car door a^2 . By means, such as the means already described, the traveller k^4 will be moved in one direction or the other across the car through the expenditure of the energy developed by the operation of the compressor as the car moves up or down, and the car door a^2 will be moved to open or to closed position, as the case may be, such movement being continued until the traveller is brought to rest by the stops which limit its movement and by the cessation of the movement of the piston f' through the operation of the valve g to cut off the supply of air behind the piston.

In the embodiment of the invention shown, the valve spindle g' has an arm g^2 , provided with a pin g^3 which is engaged in an elongated slot i' in a link i . The latter is pivotally connected to one arm of a bell crank lever i^2 , mounted on the car, the other arm of the lever having connected thereto a link i^3 to which is connected, in convenient position, a door controlling handle i^4 . The lower end of the link i^3 is connected to one arm of a bell crank i^5 , preferably mounted beneath the floor a' of the car, the other arm of the bell crank i^5 , being connected by a link i^6 with a heart-shaped cam i^7 , pivoted at i^8 . The cam i^7 co-operates with the safety

interlocking rod a^5 , previously mentioned, movement of the cam in either direction from its normal position, shown in Figure 3, lifting the rod a^5 into locking engagement with the controller a^3 and thereby preventing the starting of the car. Also mounted on the pivot i^8 of the cam i^7 is a weighted latch i^9 which is adapted to engage a stud a^6 carried by the lower end of the interlocking rod a^5 , when that rod is in its elevated position, as shown in Figure 4, thereby holding that rod in engagement with the car controller and preventing the starting of the car when the car door is in any other than its fully closed position. The latch has connected to it one end of a cord or wire i^{10} , which passes about suitable guides and has its other end connected to a weighted or spring pressed finger i^{11} which is struck by the traveller k^4 , as the door reaches its fully closed position, and is moved thereby to move the latch i^9 from engagement with the stud a^6 of the rod a^5 , thereby permitting the rod a^5 to drop, if the cam i^7 is in neutral position, and permitting the controller to be moved to start the car up or down, but only when the door a^2 is in its fully closed position. The latch i^9 is also connected, as by a cord or wire i^{12} , with the emergency handle i^{13} , so that in case of fire, for example, the operator can prevent the locking of the car controller regardless of the position of the door. The link i , which is operatively connected with the spindle g' of the valve g as hereinbefore described, through its engagement with the stud g^3 of the arm g^2 on the valve spindle g' , at the limit of its movement in either direction, effects the shifting of the connections of the valve g so as to produce the movement of the piston f' in the cylinder f , in one direction or the other, after the interlocking rod a^5 has engaged the controller a^3 to prevent the starting of the car. It will now be understood that the movement of the door controlling handle in one direction from its neutral position brings about the closing of the door and the locking of the controller and, in the other direction, the opening of the door and the locking of the controller.

The movement of the car door a^2 is made to effect corresponding movement of the shaft door opposite which the car is brought to rest. In previous arrangements this has been accomplished by providing upon the car door or upon the traveller by which it is moved, a pair of fixed, vertical shoes, spaced apart and adapted to receive between them a stud fixed to or connected to the shaft door so that movement of the car door shall effect movement of the shaft door. Such fixed shoes have been found to require careful adjustment and even then are a source of trouble through unintended contact with portions of the elevator shaft or its

equipment during the movement of the car. In the present case the shoes, which move with the car door and effect the movement of the shaft door, are themselves movably mounted on the traveller so that they may stand normally out of operative position and therefore out of position for unintended contact with parts of the elevator shaft or its equipment and may be moved into operative position only when the car operator moves the controlling handle i^4 to bring about the opening or the closing of the door. In the arrangement shown, two shoes m , suitably shaped as shown in Figures 1, 3, 8, 9 and 10, are pivotally hung, as at m' so as to swing upon vertical axes, from the inoperative position indicated by broken lines in Figure 10 to the operative position indicated by full lines in the same figure, the two shoes being spaced apart, when in operative position, so as to receive between them the coacting devices on the shaft door. The arms m^2 , both upper and lower, which carry the vertical portions of the shoes m , are provided with intermeshing gears m^3 , so that the two shoes shall move together but in opposite directions. The arms are also provided with contact faces m^4 for cooperation with an actuating member m^5 which is secured to a vertical shaft m^6 , supported in suitable bearings carried by the guide rails k^6 and located in line with the middle of the space between the shoes m when the car door is closed. The shaft m^6 is operatively connected with the bell crank i^2 , previously mentioned, so that the actuators m^5 shall be swung from their normal or neutral position, indicated by the broken lines in Figure 10, to one side or the other, as indicated by full lines in Figure 10, when the door controlling handle i^4 is moved up or down from its neutral position. In the arrangement illustrated an arm m^7 secured to the shaft m^6 has connected thereto a link m^8 which is connected at its other end to the bell crank lever i^2 . The shoes m , when free to be moved from operative position, are drawn by springs, as indicated at m^{11} in Figure 8, into inoperative position. By the movement of the actuator m^5 the shoes m , through contact of the actuator with the contact surfaces m^4 , are moved from inoperative position to operative position, this action taking place only when the door is in fully closed position. As soon, however, as the movement of the door from closed position begins and before the contact surface m^4 at one side is free from the actuator m^5 , the contact surface m^4 coacts with a holding rail m^{12} which extends across the car nearly to the position occupied by the actuator m^5 , so that, during the continued movement of the door and traveller k^4 , the shoes m are held in operative position.

65 Fixed to the shaft door b is a bracket b'

on which is pivoted a bell crank lever b^2 , one arm b^3 of which is formed as a pawl to engage a short rack b^4 fixed to the hatchway or front of the elevator shaft. Also pivoted on the bracket b' is a dog b^5 which cooperates with a pin b^6 carried by the bell crank lever b^2 . The unbalanced weight of the bell crank b^2 serves to hold the pawl b^3 normally in engagement with the rack b^4 to lock the shaft door against movement from its closed position. The upper ends of the bell crank lever b^2 and the dog b^5 are enlarged to cooperate with the shoes m . When, therefore, the door is stopped in position opposite a shaft door, the operator, by manipulation of the door controlling handle i^4 , not only effects the release of the power storage device and the operative connection of the same with the car door, but at the same time causes the shoes m to swing into operative position and thereby to disengage the latch b^3 and release the shaft door for movement with the car door through the traveller k^4 .

It will be understood that various changes in details of construction and arrangement can be made to suit different conditions of use and that, except as pointed out in the accompanying claims, the invention is not limited to the particular construction shown and described herein nor to the joint coaction of the elements referred to herein.

I claim as my invention:

1. In an elevator, the combination of a car, elevator mechanism for operating the car, a car door, an air compressor in such operative relation with the elevator mechanism that its operation will be determined by the movement of the car and transmitting devices through which the power developed by the air compressor is applied to the movement of the door.
2. In an elevator, the combination of a car, elevator mechanism for operating the car, a door, a power cylinder and piston mounted on the car, transmitting devices whereby the door is moved through the movement of the piston and an air compressor connected to the cylinder and in such operative relation with the elevator mechanism that its operation will be determined by the movement of the car.
3. In an elevator, the combination of a car, elevator mechanism for operating the car, a door, a power cylinder and piston mounted on the car, transmitting devices whereby the door is moved through the movement of the piston, an air compressor connected to the cylinder and in such operative relation with the elevator mechanism that its operation will be determined by the movement of the car and means under the control of the operator for controlling the admission of air under pressure to the cylinder.

4. In an elevator, the combination of a car, a car door, an air compressor mounted on the car, transmitting devices through which the power developed by the air compressor is applied to the movement of the door, and relatively fixed means whereby the compressor is operated upon the movement of the car.
5. In an elevator, the combination of a car, a car door, an air compressor mounted on the car, transmitting devices through which the power developed by the air compressor is applied to the movement of the door, a relatively fixed cable, and means whereby the compressor is operated through the cable upon the movement of the car.
6. In an elevator, the combination of a car, a car door, an air compressor mounted on the car, transmitting devices through which the power developed by the air compressor is applied to the movement of the door, a driving drum operatively connected to the compressor, and a relatively fixed cable engaging said drum whereby the compressor is operated upon the movement of the car.
7. In an elevator, the combination of a car, a door, a power cylinder and piston mounted on the car, transmitting devices whereby the door is moved through the movement of the piston, an air compressor also mounted on the car and connected to the cylinder, and relatively fixed means whereby the compressor is operated upon the movement of the car.
8. In an elevator, the combination of a car, a door, a power cylinder and piston mounted on the car, transmitting devices whereby the door is moved through the movement of the piston, an air compressor also mounted on the car and connected to the cylinder, relatively fixed means whereby the compressor is operated upon the movement of the car, and means under the control of the operator for controlling the admission of air under pressure to the cylinder.
9. In an elevator, the combination of a car, a movable door, a traveller mounted on the car and operatively connected to the door, a cylinder and piston operatively connected to the traveller, means to supply air under pressure to the cylinder, a valve to control the admission of air to the cylinder, valve operating means under the control of the operator, a car controller, a locking rod, means whereby the locking rod is caused by the operation of the door controlling means to engage the car controller, a latch normally engaging the locking rod to hold the same in locking position, and devices operated by the movement of the door to closed position, and operatively connected to said latch to disengage the same from the locking rod.
10. In an elevator, the combination of a car, a door, a power device mounted on the car and operatively connected to the door to move the same, door controlling means in operative relation with said power device, a car controller, a locking rod adapted to engage the car controller to prevent movement thereof, a cam actuated by movement of the door controlling devices in either direction to move the locking rod into locking position, a latch adapted to engage the locking rod and hold it in the locking position, and means operable by the car operator to disengage said latch.
11. In an elevator, the combination of a car, a door, a power device mounted on the car and operatively connected to the door to move the same, door controlling means in operative relation with said power device, a car controller, a locking rod adapted to engage the car controller to prevent movement thereof, a cam actuated by movement of the door controlling devices in either direction to move the locking rod into locking position, and means actuated by the movement of the car door to closed position to disengage the latch from the locking rod.
12. In an elevator, the combination of a shaft door, a car, a traveller mounted on the car, means to effect movement of the traveller in either direction at the will of the operator, a projecting part carried by the shaft door, a shoe mounted on the traveller and adapted to swing upon a vertical axis and to co-operate with the projection of the shaft door, and means under control of the operator to swing said shoe into operative position.
13. In an elevator, the combination of a shaft door, a car, a traveller mounted on the car, means to effect movement of the traveller in either direction at the will of the operator, a projecting part carried by the shaft door, a shoe mounted on the traveller and adapted to swing upon a vertical axis and to co-operate with the projection of the shaft door, a door controller on the car, and operative connections between said controller and said shoe whereby the shoe is moved into operative position.
14. In an elevator, the combination of a shaft door, a car, a traveller mounted on the car, means to effect movement of the traveller in either direction at the will of the operator, a projecting part carried by the shaft door, a shoe mounted on the traveller and adapted to swing upon a vertical axis and to co-operate with the projection of the shaft door, a holding bar mounted on the car to cooperate with the shoe and prevent swinging movement thereof during the movement of the traveller, and means under control of the operator to swing the shoe into operative position when the traveller is in closed position.
15. In an elevator, the combination of a

shaft door, a car, a traveller mounted on the car, means to effect movement of the traveller in either direction at the will of the operator, a projecting part carried by 5 the shaft door, a pair of shoes mounted on the traveller and connected to swing together upon vertical axes to cooperate with the projection of the door, springs tending to hold the shoes in inoperative position, 10 means under control of the operator to swing the shoes into operative position, and a holding bar mounted on the car to cooperate with the shoes to prevent swinging movement thereof in the movement of the 15 traveller.

16. In an elevator, the combination of a shaft door, a car, a traveller mounted on the car, means to effect movement of the traveller in either direction at the will of 20 the operator, a latch carried by the shaft door, a shoe mounted on the traveller and

adapted to swing on a vertical axis and to cooperate with the latch of the shaft door, a door controller mounted on the car, and operative connections between said controller and said shoe whereby the shoe is moved into operative position. 25

17. In an elevator, the combination of a shaft door, a car, a traveller mounted on the car, means to effect movement of the traveller in either direction at the will of the operator, a pair of vertical shoes mounted on the traveller and spaced apart, a latch mounted on the door to prevent movement of the door and having an arm for engagement by one of said shoes and a dog in operative relation with the latch and adapted for engagement by the other of said 30 shoes. 35

This specification signed this 14th day of 40
June, A. D. 1922.

GLENN S. WILLIAMSON.
